DESIGN FOR A GARDEN TOOL

George Pavlinetz, Carteret, N. J.

Application December 11, 1947, Serial No. 143,098

Term of patent 14 years

(Cl. D35—2)

To all whom it may concern:

Be it known that I, George Pavlinetz, a citizen of the United States of America, residing at Carteret, in the county of Middlesex, State of New Jersey, have invented a new, original, and ornamental Design for a Garden Tool, of which the following is a specification, reference being had to the accompanying drawing, forming part thereof.

Figure 1 is a top end view, Figure 2 is a side elevation, Figure 3 is an end view of Figure 2, and Figure 4 a bottom end view of a garden tool, showing my new design.

I claim:

The ornamental design for a garden tool, as shown.

GEORGE PAVLINETZ.
